UNITED STATES PATENT OFFICE.

CHESTER H. GILLIG AND LEO GILLIG, OF SAN FRANCISCO, CALIFORNIA.

AUTOMOBILE SIDE CURTAIN.

1,423,210.

Specification of Letters Patent.

Patented July 18, 1922.

Application filed January 27, 1919. Serial No. 273,208.

To all whom it may concern:

Be it known that we, CHESTER H. GILLIG and LEO GILLIG, citizens of the United States, residing at San Francisco, in the county 5 of San Francisco, State of California, have invented a new and useful Automobile Side Curtain, of which the following is a specification in such full and clear terms as will enable those skilled in the art to construct 10 and use the same.

This invention relates to the side curtains of an automobile and an object thereof is to provide suitable guides for the curtains to slide in, which guides are so positioned 15 as to enable the curtains to slide up into the top and be concealed from view, while at the same time their lower edges will move up evenly and level on both sides of the machine.

20 Another object of the invention is to enable a machine to be converted from an open into a closed machine by simply drawing the curtains down out of the top.

It will be understood by those skilled in 25 the art that owing to the downward slope of the front portion of an automobile top, that the curtain guide ways carried by the top and sides of the top, must be positioned in a particular manner so the curtains will 30 slide up evenly with their lower edges at all times level. In the present invention, the precise position of these guides is ascertained in practice by positioning a card-board pattern for the curtain with its lower 35 edge level and with the upper edge of the curtain turned horizontally and bent in accordance with the slope of the given top to which the curtains are to be applied.

Other objects of the invention will appear 40 as the description proceeds.

An embodiment of the invention is shown in the drawings in which the same reference numeral is applied to the same portion throughout, but we are aware that there 45 may be modifications thereof.

Figure 1 is a side elevation of an automobile having these curtains applied thereto.

Figure 2 is a side elevation of a top showing the position of the top ribs and 50 guides.

Figure 3 is a vertical sectional view of a portion of the top showing the arrangement of the ribs and guides.

Figure 4 is a transverse sectional view of 55 the top taken on the line 4-4, Figure 3, and looking in the direction of the arrow,

Figure 5 is a side elevation of one of the curtains showing the construction of the frame.

Figure 6 is a side elevation of a modified 60 form of a detachable guide used in the place of the swing guide shown in Figures 1 and 2.

Figure 7 is a plan view of the top with the covering and lining removed, and 65

Figure 8 is a perspective view of the curtain as it appears when bent and partly raised under the top.

In the drawings:

The numeral 1 indicates the automobile 70 which is provided with the top 2 having suitable windows at 3 on each side and connected with the wind shield at 4 in such a manner as to provide a guide for the front edge of the front curtain in the space between the front part of the top and the portion at the front of the window 3. There are two sliding curtains 5 and 6 on each side of the machine. These curtains move in a guide 7, double guide bar 8 and single 80 guide 9.

The guide 8 is pivotally mounted at 10 so that it will swing up out of the side under the edge of the covering of the bows as indicated in Figure 2; and when it is down 85 it is held in that position by a turn button 11 which passes through the hole in said guide bar.

The top is provided with longitudinally extending bars 12, 13 and 14 and it has suitable bows 15 and 16 to hold the top covering in the proper shape, a cross bar 17 at the back connecting the side bars 12 and 14, and the latter two bars are connected at the front by a cross bar 18. While the 95 edges of the curtain slide in the vertical guides 7, 8, 9, and 7', 8', 9', at both sides of the machine it is necessary for the curtains to move in the guides at an angle to the longitudinal axis of the top other than 90 degrees on account of the front slope thereof. This inclination is shown in the guides 20 to 25 inclusive in Figure 7.

The curtains themselves are each made up of a flat, rectangular, flexible frame having 105 the sides 26 to 29 inclusive and covered with a suitable cloth facing 30 secured to a sheet of flexible transparent window material 31. When the guides are in place the interior of the top is covered with a lining 33 so that 110 when the curtains are up they are completely concealed.

If it is desired to remove the double guide from the machine altogether, the form shown in Figure 6 may be used in which the double guide 35 is shown connected to the top guide 36 by means of a turn button 37, and with the body 38 by means of a turn button 39. In this event the guides at both sides of the machine are simply removed altogether and stowed in a convenient receptacle until desired for use.

What we claim is as follows, but various modifications may be made in the construction shown in the drawings and above particularly described form, within the pur-
view of our invention.

1. A disappearing curtain for automobile tops comprising a top having bows, a series of guideways supported by the bows, the guideways extending rearwardly toward the center of the top, and flexible curtains slide-
able in the guideways.

2. A disappearing curtain for automobile tops comprising a top having bows, a series of guideways carried thereby the guideways extending rearwardly toward the center of the top, a central longitudinal member to which the ends of the guideways are connected, a movable bar having guideways in

opposite edges and connecting the center guideway with the automobile body, and curtains slideable in the guideways concealed under the top when not in use.

3. A disappearing curtain for automobile tops comprising an automobile top having supporting bows, a series of guideways supported by the bows the guideways lying below the plane of the bows in their upper portion, two sets of curtains slideable along the guideways at opposite sides of the top, and a bar detachably connected to the automobile body and having guideways in opposite edges thereof to receive the front and rear curtains the upper portions of the guideways extending rearwardly toward the center of the top whereby the curtains may be raised with their lower edges level in all positions.

In testimony whereof we have hereunto set our hands this 21st day of January, A. D. 1919.

CHESTER H. GILLIG.
LEO GILLIG.
